HEAT PUMP

Eugene R. Ambrose, Cranford, N. J., assignor to
General Electric Company, a corporation of
New York

Application June 26, 1941, Serial No. 399,840

11 Claims. (Cl. 62—6)

My invention relates to air conditioning systems and particularly to such systems which utilize heat pumps or reversible refrigerating machines for both heating and cooling.

A refrigerating machine may be utilized in an air conditioning system for both heating and cooling by providing some suitable arrangement for selectively reversing the direction of flow of heat between the air in the enclosure or room to be conditioned and the outdoor air or other medium employed for supplying or removing heat. For example, the refrigerant circuit of the refrigerating machine of a cooling system may be reversed for heating so that the evaporator becomes a condenser and the condenser an evaporator, or the air paths of such a system may be reversed to change from the cooling to the heating operation so that the air for the enclosure flows over the condenser instead of over the evaporator while the external medium flows over the evaporator instead of over the condenser.

It is an object of my invention to provide an air conditioning system employing a refrigerating machine as a heat pump and including an improved arrangement for controlling selectively the air paths over the heat absorbing and heat dissipating surfaces of the refrigerating machine.

Another object of my invention is to provide an air conditioning system including a refrigerating machine having heat absorbing and heat dissipating surfaces arranged for the circulation of air thereover, and having an improved arrangement for controlling the system including the air paths thereof to provide a more effective utilization of the capacity of the refrigerating machine.

Further objects and advantages of my invention will become apparent as the following description proceeds and the features of novelty which characterize my invention will be pointed out with particularity in the claims annexed to and forming a part of this specification.

For a better understanding of my invention reference may be had to the accompanying drawings in which Fig. 1 is a diagrammatic view of an air conditioning system embodying my invention; Fig. 2 is a line-to-line diagram of the electrical control circuit for the system shown in Fig. 1; and Figs. 3 to 6 inclusive, are diagrammatic views similar to Fig. 1 illustrating the several positions of the dampers for controlling the flow of air.

Briefly, the air conditioning system illustrated in the drawings comprises a refrigerating machine including a compressor, a condenser and

5 two evaporators connected in a closed refrigerant circuit, the evaporators being connected in parallel in the refrigerant circuit. A duct structure is provided to form three air circulating zones as shown each having a blower or air circulating fan for directing air therethrough. The compressor and condenser are arranged in the first zone, one evaporator in the second zone, and the other evaporator in the third zone. During the heating season, air for the enclosure to be heated is circulated over the condenser and compressor unit in the first zone and outdoor air over the evaporators in the other zones. During the cooling season outdoor air is circulated through the first zone and air to be cooled and admitted to the enclosure is circulated through the third zone, and under certain conditions of operation the blower in the second zone may be employed as a booster to augment the circulation of outdoor air 10 produced by the blower in the first or in the third zone. The control of the dampers is automatic and is effected in accordance with changes in the requirements of the system as determined, for example, by the temperature of the outdoor air.

15 Referring now to the drawings in Fig. 1, I have shown an air conditioning system comprising a duct structure or housing 10 providing three zones or compartments 11, 12, and 13 through which air may be circulated by operation of 20 motor-driven fans 14, 15 and 16, respectively. The air flowing through the compartment 11 may be heated and the air flowing through compartments 12 and 13 may be cooled by operation of 25 a refrigerating machine comprising a compressor 17, driven by a motor 18, a condenser 19 and evaporators 20 and 21 all connected in a closed refrigerant circuit. The compressor unit and the condenser constitute heat dissipating elements and the evaporators constitute heat absorbing elements. The compressor 17 and the motor 18 are arranged in the compartment 11 and the condenser 19 is arranged in a discharge hood 22 in the outlet of the compartment 11. The fan 14 is driven by a motor 23 mounted in 30 the inlet of the hood 22. The compressor 17 delivers hot compressed refrigerant to the condenser 19 through a connection 24, and refrigerant liquefied in the condenser 19 flows to a liquid receiver 25 within the compartment 11. The fans 15 and 16 are driven by motors 37 and 38, respectively, arranged in inlet connections 39 and 40 of their respective compartments. 35 Evaporators 20 and 21 are connected in parallel in the refrigerant circuit by liquid lines 26 and 27, respectively, and suction lines 28 and 29, re-

spectively. Vaporized refrigerant flowing from the refrigerator through the suction lines 28 and 29 returns to the compressor through a common suction line 30. A normally closed valve 31 is arranged in the liquid line 26 and may be operated by a solenoid 32 to admit refrigerant to the evaporator 20, the flow of refrigerant being controlled by a thermostatic expansion valve 33 in the usual manner. Similarly, a normally closed valve 34 is provided in the connection 27 and may be opened by operation of a solenoid 35 to admit refrigerant to the evaporator 21, the flow of refrigerant being controlled by a thermostatic expansion valve 36.

A system of duct work is provided so that either room air or outdoor air may be circulated through the three compartments and discharged to the outdoors, or to the room, depending on the conditions of operation of the system. The compartment 11 is provided with an inlet duct 41 arranged to receive outside or fresh air from an inlet 42 under control of dampers 43 and to receive room air through an inlet 44 under control of dampers 45. The air circulated through the compartment 11 is discharged through a duct 46 and may enter the room through an outlet 47 under control of dampers 48 or may be discharged to the outdoors through an outlet 49 under control of dampers 50. The compartment 12 is provided with an outdoor air inlet duct 51 and the compartment 13 is provided with a room air inlet duct 52 for receiving air from the room under control of dampers 53. A cross-duct 54 is arranged between the ducts 51 and 52 and is provided with control dampers 55 having a minimum closed position determined by a stop 56. The duct 54 makes it possible to admit outdoor air from the duct 51 to the compartment 13. Air may be discharged from the compartment 12 to the outdoors through a duct 57 under control of dampers 58, and air may be discharged from the compartment 13 through a duct 59 and into the room through an outlet 60 controlled by dampers 61 or into the duct 57 through a cross-duct 62 under control of dampers 63. Between the compartments 11 and 12 there is provided a duct or connection 64 controlled by dampers 65 so that air may be circulated from the compartment 12 into the compartment 11. All of the dampers above referred to are of the normally closed type and may be actuated to their open positions by the operation of solenoids in a manner to be described.

The air conditioning system just described may be employed for maintaining the desired air conditioning temperature in the room throughout all the seasons of the year.

During the heating season air is circulated through the compartment 11 and is discharged into the room through duct 47, the dampers 45 and 48 being open and the dampers 43 and 50 being closed. Some fresh air will be taken in at all times since the dampers 43 are provided with a stop 66 for preventing their complete closing. When the system is being employed in this manner to heat the air in the room, outdoor air is circulated through one or both of the compartments 12 and 13 and is returned to the outdoors through the duct 57. The dampers 58 are open when the compartment 12 is employed and the dampers 66 and 63 are also open when both compartments are employed, in which case, the dampers 53 and 61 are closed. By circulating outdoor air over the evaporators, heat is absorbed from the air flowing through the compartments

12 and 13 and is supplied to the air flowing through the compartment 11, the heat being dissipated to the air by the condenser and compressor unit.

5 During the cooling season, the dampers 43 and 50 are kept open to circulate outdoor air through the compartment 11 and remove heat from the refrigerating apparatus while room air is circulated through the compartment 13 and back into the room through the opening 60, dampers 53 and 61 being open. The air admitted to the compartment 13 may be a mixture of room air and fresh air drawn in through the dampers 55 in their limited closed position, or it may be entirely outdoor air provided the dampers 53 are closed and the dampers 55 opened. The evaporator 20 is not normally used to cool air during the cooling season but the fan 15 may be employed to augment the flow of outdoor air through the compartment 11 by opening the dampers 65 thereby providing a booster for the fan 14.

10 The operation of the system during the heating season is controlled by a heating thermostat 70 and the operation during the cooling season is controlled by a cooling thermostat 71; the control of the air paths has been shown as effected in accordance with the operation of four thermostats 12, 13, 74 and 75 all responsive to the temperature of the outdoor air, although it is obvious that other load responsive control or manual control might be employed. The manner in which the control is effected will readily be apparent from the control diagram shown in Fig. 2. Power for energizing the control circuits and for driving the fan and compressor motors is supplied from power lines 76 and 77 and a manual switch 78 is provided to interrupt the power supply.

15 In the following description, in order to provide an example of the setting of the controls, it is assumed that the thermostat 72 closes its contacts when the outdoor air is above 65° F., the thermostat 73 closes its contacts when the temperature is above 60° F., the thermostat 74 closes its contacts when the temperature is below 60° F., and the thermostat 75 closes its contacts when the outdoor temperature is below 50° F. In the drawings, only the thermostat 73 has been indicated in its closed position in which case the temperature would be below 65° F. and above 60° F.

20 In the following, the operation of the system will be described assuming that the manual switch 78 is closed to start the operation at a time when the outdoor temperature is below 50° F. and that the operation of the system continues while the outdoor temperature rises to a temperature higher than 65° F.

25 At temperatures below 50° F. the entire heating capacity of the refrigerating machine is made available, both thermostats 74 and 75 being in their closed positions. When the switch 78 is closed the thermostat 75 actuates a solenoid 79 of a four-armed switch 80 and moves the switch to its upper or closed position. The lowest arm of the switch closes the circuit of a solenoid 81 which actuates the dampers 63 to their open position. The next lowest arm of the switch closes the circuit of a solenoid 82 which moves the dampers 55 to their open position. The third switch arm from the bottom closes the circuit of the solenoid 35 to open the refrigerant supply valve 34 of the evaporator 21, and the top arm of the switch 80 closes the circuit of fan motor 38 to start the operation of fan 16.

The thermostat 74 in its closed position energizes a solenoid 83 of a four-armed switch 84 and closes the switch. The lowermost contact arm of the switch closes the circuit of solenoids 85, 86 and 87 connected in parallel and arranged to actuate the dampers 45, 48 and 58 respectively to their open positions. The next arm of the switch 84 prepares the circuit of the solenoid 32 so that it may be operated on a demand for heat determined by the thermostat 70. The third arm from the bottom of switch 84 prepares the circuit of the compressor motor 18 so that the compressor will be started on a demand for heat, and the top arm of the switch 84 closes a circuit of the fan motors 23 and 37 connected in parallel, thereby starting the fans 14 and 15. All the fan motors are thus started upon closing of the manual switch 78, and the dampers 45, 48, 55, 58 and 63 are opened. The circulating air paths for this position of the control are illustrated in Fig. 3 of the drawings from which it is evident that a mixture of fresh air and room air is circulated through compartment 11 and into the room while outdoor air is circulated through both compartments 12 and 13 over the evaporators and back to the outdoors. Upon a demand for heat the thermostat 70 will close its contacts thereby connecting a solenoid 88 in the secondary circuit of a transformer 89 and actuating a four-armed switch 90 to its upper position. The two lower arms of the switch 90 complete the circuits of the solenoid 32 and of the compressor motor 18 and the refrigerating machine is thereby operated, so that the evaporators 20 and 21 absorb heat from the outdoor air circulated through the compartments 12 and 13 and the air circulated through the compartment 11 is heated by the compressor unit and the condenser and then supplied to the room. When the thermostat 70 is satisfied and opens its contacts 40 operation of the refrigerating machine is stopped, however, the circulation of air continues. When the outdoor air reaches a temperature above 50° F. the thermostat 75 opens its contacts and the switch 80 drops out thereby deenergizing the solenoids 81 and 82 and allowing the dampers 64 and 65 to return to their closed positions; at the same time the two upper arms of the switch 80 opens the circuits of the fan motor 38 and the solenoid 35 thereby stopping the operation of the fan 16 and shutting off the supply of refrigerant to the evaporator 21. In this position of the controls the compartment 13 is not utilized to augment the flow of outdoor air which now is circulated only through the compartment 12 and over the evaporator 20 as shown in Fig. 4; and upon a demand for heat there will be a smaller evaporator surface for the absorption of heat from the outdoor air. The capacity of the refrigerating machine has thus been reduced in view of the decreased load requirement as determined by the outdoor temperature.

As the outdoor temperature continues to rise and reaches a temperature of 60° F., the thermostat 74 opens its contacts and deenergizes the solenoid 83 causing the switch 84 to drop out, thereby deenergizing solenoids 32, 85, 86 and 87 to close the valve 31 and stop the operation of the evaporator 20 and to allow the dampers, 45, 48 and 58 to move to their closed positions. The fan motors 23 and 37 and the compressor motor 18 are also deenergized so that the entire system is shut down momentarily, however, as soon as the temperature increases to a value above 60° F. the thermostat 73 will close its contacts and 75

energize a solenoid 91 of a four-armed switch 92. The lowermost arm of the switch 92 prepares a circuit of a solenoid 93 for operating the dampers 53 upon a call for heat by the thermostat 70. The next to the lowest arm of the switch 92 energizes the circuit of the solenoid 82 to open the dampers 55 provided the thermostat 70 is not calling for heat. The second arm from the top of the switch 92 energizes the circuit of a solenoid 94 to open the dampers 61, and the top arm of the switch 92 energizes a circuit of the fan motor 38 to start the operation of the fan 16. The operation of the refrigerating system between temperatures of 60° F. and 65° F. is indicated in Fig. 5; this position of the apparatus is such that outdoor air is brought into the compartment 13 through the cross-duct 54, the dampers 55 being open and the air is circulated through the compartment 13 and flows into the room through the outlet 60, the dampers 61 being open. The refrigerating machine is not in operation. Should the thermostat 70 call for heat, the switch 90 will be moved to its upper position thereby deenergizing the solenoid 82 since the top arm of the switch 90 opens the circuit established by the next to the lowest arm of the switch 92. This closes the dampers 55 so that only the minimum amount of fresh air is drawn into the compartment 13 and at the same time the second arm from top of the switch 90 closes the circuit of the solenoid 93 established by the lowermost arm of the switch 92 and thereby opens the dampers 53 so that room air is recirculated by operation of the fan 16. The refrigerating machine remains idle.

As the outdoor temperature continues to rise to a value greater than 65° F. the thermostat 72 closes its contacts to energize a solenoid 95 of a five-armed switch 96. The middle arm of the switch 96 energizes the circuit of three solenoids 97, 98, and 99 which open the dampers 43, 50 and 65, respectively. The bottom arm of the switch 96 closes a circuit energizing the motors 23 and 37 and starts the operation of the fans 14 and 15, the next to the bottom arm of the switch 26 closes the solenoid 93 thereby opening the dampers 53. The top arm of the switch 96 prepares a circuit of the solenoid 35 so that the valve 34 will be opened upon a demand for cooling determined by the thermostat 71, and the next to the top arm of the switch 96 prepares a circuit of the compressor motor 18. Should there be a demand for cooling, the thermostat 71 closes its contacts and connects a solenoid 100 across the primary winding of a transformer 101 thereby picking up a switch 102 and energizing the circuits of the solenoid 35 and the motor 18 to start the refrigerating machine. The operation of the system during this period is indicated in Fig. 6. Outdoor air is circulated through the compartment 11 from the inlet 42 to the outlet 49 by operation of the fan 14, and the flow of outdoor air through the compartment 11 is augmented by the operation of the fan 15 which circulates outdoor air from the connection 51 through the compartment 12 and into the compartment 11 through the connection 64. A mixture of room air and outside air is circulated from the connection 52 through the compartment 13 and into the room, the dampers 53, 55 and 61 being in their open positions. The air for the room is cooled by operation of the refrigerating machine which is connected to supply refrigerant to the evaporator 21. The evaporator 20 is not in use and the dampers 58 are closed.

This is the position of maximum capacity of the refrigerating system during the cooling season.

During the cooling season, whenever the thermostat 11 is not calling for cooling, the refrigerating machine is idle, but the fans continue to operate and circulate air through the several compartments. Should the suction pressure or back pressure of the compressor decrease below a predetermined minimum permissible value a bellows 103 will contract and open a switch 104 thereby opening the circuit of the compressor motor 18 and preventing operation of the compressor until the suction pressure again rises to the working range.

The operation of the air conditioning system as described above will be effected in reverse order when the outdoor temperature falls from 65° F. to a temperature below 50° F. It is readily apparent that the system will operate over a wide range of outdoor temperatures providing either heating or cooling as required and that it will modify the capacity of the refrigerating machine depending upon the temperature of the outdoor air. The operation of the system is automatic after it has been started by closing the manual switch 78. The system will continue to maintain the desired range of temperature under control of the thermostat 10 during the cooling season and under control of the thermostat 11 during the heating season. The direction of flow of heat between the enclosure and the outdoors may be varied without the necessity of reversing or otherwise changing the refrigerant circuit. The several compartments of this system and the circulating fans are so arranged that the most desirable conditions of operation are maintained automatically for any given outdoor temperature.

Although I have described my invention in connection with an air conditioning system, other applications will readily be apparent to those skilled in the art. I do not, therefore, desire my invention to be limited to the particular construction shown and described and I intend in the appended claims to cover all modifications within the spirit and scope of my invention.

What I claim as new and desire to secure by Letters Patent of the United States is:

1. An air conditioning system including a first compartment and a second compartment and a third compartment, each of said compartments being provided with a separate air inlet and a separate blower for circulating air therethrough, and means including dampers for determining selectively the paths of air flowing from said inlets through said compartments, said means being operable in one position of said dampers to utilize the blower of said second compartment for assisting the blower in said first compartment to augment the circulation of air produced by the blower in said first compartment by the addition of air flowing from the inlet of said second compartment and being operable in a second position of said dampers to utilize the blower of said second compartment to assist the blower in said third compartment to augment the flow of air circulated by the blower in said third compartment by the addition of air flowing from the inlet of said second compartment.

2. A system for conditioning the air in an enclosure including a first compartment and a second compartment and a third compartment, each of said compartments being provided with a separate blower for circulating air therethrough, a refrigerating machine including a heat dissipat-

ing element in said first compartment and heat absorbing elements in said second and third compartments, damper means operable in a first position for affording a circulation of air from said enclosure through said first compartment and back to said enclosure and in a second position for affording a circulation of air from outside said enclosure through said first compartment and back to the outside, damper means operable in a first position for affording a circulation of outside air through said third compartment to the outside and in a second position for affording a circulation of air from the enclosure through said third compartment and back to the enclosure, damper means operable in a first position for affording a circulation of outside air through said second compartment and in a second position for utilizing the fan in said second compartment to force outside air into said first compartment, means dependent upon a predetermined low temperature of the air outside said enclosure for actuating said three damper means to their first positions and dependent upon a predetermined higher temperature of the air outside said enclosure for actuating said three damper means to their second positions.

3. A system for conditioning the air within an enclosure including a refrigerating machine having a heat dissipating element and two heat absorbing elements, each of said elements having a separate fan for circulating air thereover, and means selectively operable into a first position for utilizing said refrigerating machine to heat the air in the enclosure and into a second position for utilizing said refrigerating machine to cool the air in the enclosure, said means in said first position directing outside air over both said heat absorbing elements and directing air circulated over said heat dissipating element into the enclosure, said means in said second position directing outside air over said heat dissipating element and directing air circulated over one of said heat absorbing elements into the enclosure and utilizing the fan of the other of said heat absorbing elements to augment the circulation of outside air over said heat dissipating element.

4. A system for conditioning the air within an enclosure including a refrigerating machine having a heat dissipating element and two heat absorbing elements, each of said elements having a separate fan for circulating air thereover, and means selectively operable into first and second positions for utilizing said refrigerating machine to heat the air in the enclosure and into a third position for utilizing said refrigerating machine to cool the air in the enclosure, said means in said first position directing outside air over both of said heat absorbing elements and directing air circulated over said heat dissipating element into the enclosure, said means in said second position directing outside air over one only of said heat absorbing elements and directing air circulated over said heat dissipating element and into the enclosure, said means in said third position directing outside air over said heat dissipating element and directing air circulated over one of said heat absorbing elements into the enclosure and utilizing the fan of the other of said heat absorbing elements to augment the circulation of outside air over said heat dissipating element.

5. An air conditioning system including a refrigerating machine for heating and for cooling the air in an enclosure, said refrigerating machine including a heat dissipating element and two heat absorbing elements, each of said elements

having an individual fan for circulating air thereover, and air control means selectively operable to a first position to utilize said machine to pump heat into the enclosure and selectively operable to a second position for utilizing said machine to pump heat out of the enclosure, said means in its first position being arranged to direct outside air over said two heat absorbing elements and to direct air over said heat dissipating element and into the enclosure and in its second position to direct outside air over said heat dissipating element and to direct air over one of said heat absorbing elements and into the enclosure, said means in its second position utilizing the fan of the other of said heat absorbing elements to augment the flow of air over said heat dissipating element.

6. An air conditioning system including a refrigerating machine for heating and for cooling the air in an enclosure, said refrigerating machine including a heat dissipating element and two heat absorbing elements, each of said elements having an individual fan for circulating air thereover, and air control means selectively operable to a first position to utilize said machine to pump heat into the enclosure and selectively operable to a second position for utilizing said machine to pump heat out of the enclosure, said means in its first position being arranged to direct outside air over said two heat absorbing elements and to direct air over said heat dissipating element and into the enclosure and in its second position to direct outside air over said heat dissipating element and to direct air over one of said heat absorbing elements and into the enclosure, said means in its second position utilizing the fan of the other of said heat absorbing elements to augment the flow of air over said heat dissipating element, and means dependent upon a predetermined temperature of the outside air for operating said air control means to its first position and dependent upon a predetermined higher temperature of the outside air for operating said air control means to its second position.

7. An air conditioning system including a refrigerating machine for heating and for cooling the air in an enclosure, said refrigerating machine comprising a condenser and a compressor and two evaporators connected in a closed refrigerant circuit, valve means for shutting off the supply of refrigerant to one of said evaporators, a fan for circulating air over said condenser, individual fans for circulating air over each of said evaporators, and air control means selectively operable to a first position to utilize said machine to pump heat into the enclosure and selectively operable to a second position for utilizing said machine to pump heat out of the enclosure, said air control means in its first position being arranged to direct outside air over said two evaporators and to direct air over said condenser and into the enclosure and in its second position to direct outside air over said condenser and to direct air over the other one of said evaporators and into the enclosure, said air control means in said second position actuating said valve means to cut off the flow of refrigerant to said one evaporator and utilizing the fan of said one evaporator to augment the flow of air over said condenser.

8. An air conditioning system including a refrigerating machine for heating and for cooling the air in an enclosure, said refrigerating machine comprising a condenser and a compressor

and two evaporators connected in a closed refrigerant circuit, valve means for shutting off the supply of refrigerant to one of said evaporators, a fan for circulating air over said condenser, individual fans for circulating air over each of said evaporators, and air control means selectively operable to a first position to utilize said machine to pump heat into the enclosure and selectively operable to a second position for utilizing said machine to pump heat out of the enclosure, said air control means in its first position being arranged to direct outside air over said two evaporators and to direct air over said condenser and into the enclosure and in its second position to direct outside air over said condenser and to direct air over the other one of said evaporators and into the enclosure, said air control means in said second position actuating said valve means to cut off the flow of refrigerant to said one evaporator and utilizing the fan of said one evaporator to augment the flow of air over said condenser, and temperature responsive means dependent upon temperatures of the outside air below a predetermined temperature for actuating said air control means to its first position and dependent upon temperatures of the outside air above a predetermined temperature for actuating said air control means to its second position.

9. An air conditioning system including a refrigerating machine for heating and for cooling the air in an enclosure, said refrigerating machine comprising a condenser and a compressor and two evaporators connected in a closed refrigerant circuit, means providing a first compartment and including a fan for circulating air first over said compressor and then over said condenser, means providing a second compartment and including a fan for circulating air over one of said evaporators, means providing a third compartment and including a circulating fan for circulating air over the other of said evaporators, valve means for shutting off the supply of refrigerant to said one of said evaporators, and damper means selectively operable to a first position to utilize said machine and said fans to pump heat into the enclosure and selectively operable to a second position to utilize said machine and said fans to pump heat out of the enclosure, said damper means in its first position being arranged to direct outside air through said second and third compartments and to direct air through said first compartment and into the enclosure and in its second position to direct outside air through said first compartment and to direct air through said third compartment and into the enclosure, said damper means in said second position actuating said valve means to cut out the flow of refrigerant to said one evaporator and utilizing the fan in said second compartment to circulate air from said second compartment into said first compartment intermediate said compressor and said condenser to augment the flow of air over said condenser.

10. A system for conditioning the air within an enclosure including a refrigerating machine having a heat dissipating element and a heat absorbing element, a fan associated with said heat dissipating element for circulating air thereover, a fan associated with said heat absorbing element for circulating air thereover, thermostatic means dependent upon the temperature of the air in said enclosure for controlling the operation of said refrigerating machine, means dependent upon a temperature of the outdoor air above a first predetermined temperature for directing into the

enclosure air circulated over said heat absorbing element and for rendering said thermostatic means effective to control the operation of said refrigerating machine, means dependent upon a temperature of the outdoor air below a second predetermined temperature for directing into the enclosure air circulated over said heat dissipating element and for rendering said thermostatic means effective to control the operation of said refrigerating machine, and means dependent upon temperatures of the outdoor air in the range between said first and second predetermined temperatures for maintaining said refrigerating machine inactive and for circulating air from the enclosure over one of said elements and back to the enclosure.

11. A system for conditioning the air within an enclosure including a refrigerating machine having a heat dissipating element and a heat absorbing element, a fan associated with said heat dissipating element for circulating air thereover, a fan associated with said heat absorbing element for circulating air thereover, thermostatic means dependent upon the temperature of the air in said enclosure for controlling the operation of

said refrigerating machine, means dependent upon a temperature of the outdoor air above a first predetermined temperature for directing into the enclosure air circulated over said heat absorbing element and for rendering said thermostatic means effective to control the operation of said refrigerating machine, means dependent upon a temperature of the outdoor air below a second predetermined temperature for directing into the enclosure air circulated over said heat dissipating element and for rendering said thermostatic means effective to control the operation of said refrigerating machine, and means dependent upon temperatures of the outdoor air in the range between said first and second predetermined temperatures for circulating outdoor air over one of said elements and into the enclosure when said thermostatic means is satisfied and for circulating air from the enclosure over said one of said elements and back to the enclosure upon a demand for heat by said thermostatic means, said refrigerating machine remaining inactive when the outdoor temperature is within said range.
